LEG ASSEMBLY FOR FURNITURE

David S. Haven, Richmond Heights, Mo., assignor
to Meier & Pohlmann Furniture Company, St.
Louis, Mo., a corporation of Missouri

Application January 26, 1951, Serial No. 208,061

2 Claims. (Cl. 311—110)

1

This invention relates to improvements in leg assemblies for furniture, and more particularly to an improved leg-locating and attachment agency for the assembly of legs to various articles of furniture, such as tables, chairs and the like.

In the manufacture of tables and certain other articles of furniture, it has long been a conventional practice to utilize a so-called corner block in conjunction with the aprons or rails of a table. Such corner block is conventionally glued or nailed into place, and usually coacts with the upper end of the leg for securing thereof in proper location and angularity with respect to the horizontal supporting surface thereabove, such as a table top. According to such prevailing practice the corner block must be separately secured to the aprons, and the leg in turn secured to the corner block and sometimes also to the aprons, requiring several separate assembly operations and the separate cutting and handling of an element now found unnecessary. The elimination of such older parts and assembly steps by present improvements, results in a reduction in number of elements to be assembled, cut, and stocked. It is accordingly a major objective of the present improvements to eliminate the corner blocks prevalently used in the cornering regions of the aprons or rails, to obviate the several cost items and assembly expense incident thereto, and at the same time materially enhancing the rigidity of the article of furniture.

Further objects and advantages of the present improvements include the formation of leg-locating recesses as integral parts of the rail or apron elements of a table, for example.

Still another and important object of the present invention is found in an improved location and arrangement of bias-cut leg-locating seats on the aprons, and an improved manner of bolted securement of the leg elements to the parts of the table.

A still further and highly important objective realized in the present subject matter, arises from the greatly improved knock-down facilities afforded by the novel mode of assembly; for example, less likelihood of damage in transit, and greater certainty of proper erection of the table or the like with the legs accurately located and rigidly assembled.

The foregoing and still further objectives and advantages will more clearly appear from the following detailed description of a currently preferred embodiment, particularly when reference is made to the accompanying drawing, in which:

Fig. 1 is a fragmentary side elevational view, partly in section, of a corner portion of a table, the leg assemblies of which embody present improvements;

Fig. 2 is a bottom plan view of the structure of Fig. 1 as viewed along line 2—2, and

Fig. 3 is a plan view of an end portion of one of the end aprons, showing formation thereof in embodiment of the present improvements.

Referring now by characters of reference to the drawing, the improvements will be described by reference to a table and leg assembly but without limitation thereto, since the same or virtually the same principles of construction are equally applicable to certain types of chairs and other furniture items. There is shown by the drawing a table top TT which may be of any suitable shape, form or design, and which will in most cases constitute a substantially horizontal primary support for the burden imposed thereon. The table top as such is or may be of conventional or any desired construction, usually a planar element of wood.

Arranged in the form of a substantially rectangular frame structure immediately beneath the table top TT, are four aprons or rails, the end aprons being indicated at 10 and the side aprons at 11. Each of these aprons is shown as provided with a series of countersunk screw recesses 12 for the reception of attachment screws 13, by which the rails are edgewise secured and bear a depending relation to the top TT, forming the primary support therefor. It is desirable that the cornering portions of each end apron 10 and each side apron, be provided with a tongue-and-slot form of interfitting joint such as shown by Fig. 2, and in which the slot is indicated at 14 and the tongue at 15.

In the example shown, each end apron 10 is formed in a corner region slightly spaced from the corner apex of the adjacent aprons, to provide a pair of opposed, parallel, oblique faces one of which shown at 16 is on the outside, and another such face 17 located on the inside of each end of each apron 10. These oblique faces are shown as located at about a 45 degree relation to the parallel side faces 20 of the apron 10, and the opposite parallel faces 16, 17 are connected by a 45 degree bolt passage or bore 21 for the reception of a hanger bolt, as will later appear. The bores 21 and the bolts are shown in pairs, one pair of bores and bolts being vertically spaced in each corner.

Each of the side aprons 11 is extended somewhat outwardly of the exact corner region, each

such extension being indicated at 22 and provided at its outer end with an oblique face 23 which, as shown, is disposed about at a right angle to each of the parallel faces 16, 17 on the companion cornering apron 10. Each of the oblique faces 16 and 17 partly defines a V-shape notch, that on the outside of each corner region of apron 10 being indicated at 24, and the notch lying opposite the first said recess being indicated at 25.

With this arrangement, it is a matter of considerable preference that the aprons 10 and 11 each be located somewhat inwardly of the outermost margins of the furniture top TT, particularly so in case the leg elements, usually four in number and designated generally at L, are located externally of the cornering aprons as shown.

The contouring or design of the several leg elements is a matter of choice consistent with structural requirements and specific design of the article of furniture with which they are used. Particular reference should, however, be made to the upper end portion of each of the legs L, shown as being of a generally rectangular cross section, but with a rounded outer marginal portion. The opposite portion 26 of the upper end of each leg, is by preference of an angular cross section, assuming that the same relation prevails between the two oblique faces defining the notch 24. This latter should in any case conform to the sectional contouring of the upper end of the leg L, so that when the leg is inserted in place with one corner thereof seated in the V notch 24, the notch serves accurately to locate the leg prior to as well as after final assembly thereof to the table. It has been found conducive to snugness of assembly to form the notch 24 on slightly less than a true 90 degree angle, say 87°-89°, so that a wedging action on the leg results when bolted into assembly. While any suitable assembly hardware may be utilized, it is a preference, to assure a sturdy and rigid attachment of the legs to the aprons, that metal hanger bolts be employed. Such items of hardware are well known, and constitute per se no part of the present improvements apart from the combination. The hanger bolt illustrated includes a lag end HBL which is threaded in a horizontal direction along the major transverse axis of each leg L, and is preferably installed in the leg prior to shipment. The opposite end of the hanger bolt is machine screw threaded so as to accept a nut N overlying a washer W, the washer bearing against the oblique face 17 which is opposite to but in paired relation with the oblique face 16 earlier described. Each hanger bolt HB is of a length to extend through the bore 21, as will be apparent from the drawing, and a pair of bolts HB are preferred in each corner.

It is desirable to maintain a fixed relation of the apron elements prior to attachment thereof to the top TT, and for this purpose there is provided in each corner region a conventional corrugated fastener or nail. Although optional, it has in some cases been found conducive to added leg rigidity in assembly, to provide a fastening nail or the like, indicated at 30, driven at an acute angle through the upper leg, axially into the extension of the side rail.

The manner of assembly and the advantages in use of the structure heretofore described, are thought to have become apparent from the foregoing detail of description, but it may be noted for completeness that, in keeping with usual production practice, the table top TT or like element

will be separately fully formed and finished as will the side and end aprons or rails 10 and 11, it being noted that by the use of automatic equipment the apron elements will be shaped and smoothed preferably in continuous production operations as a part of which there are formed in and on the described regions of the aprons, the oblique faces 16, 17 and the notches 24 and 25, as well as the oblique end face 23 on each extension of the side aprons. Drilling of the passages or bores 21 for the hanger bolts in each of the four locations therefor may be done in accordance with conventional practice.

Assuming completion of the table top TT the 15 aprons are assembled in final relative relation through interfitting of the tongues 15 and the companion grooves 14 therefor, temporary securing of these elements in each corner region being effected by a corrugated nail as earlier 20 mentioned. The aprons will have been provided with screw recesses 12. The four aprons arranged substantially as a rectangular enclosure, may now be disposed on the lower face of the table top and assembled thereto as by screws 13. The 25 hanger bolts are installed in the legs, in a substantially horizontal position and threaded edge-wise into the upper region of each leg substantially in the location shown. Shipment of the table elements will for economy usually be made 30 with the legs separate from the top assembly as described, and thus in knock-down relation ready for erection at the situs of usage. Final assembly of the legs to the top and apron structure will, now obviously, be effected by locating each of the 35 legs L with its upper corner region in one of the notches 24, and with the hanger bolts HB extended through the adjacent bores 21 therefor. Application of the washer and nut N to each of the hanger bolts, and a tight take-up of the nuts, 40 will complete the assembly of the legs but for driving of the nail or screw 30, if and when utilized.

It will have appeared that the snug, interfitting relation between the upper leg portion and the 45 locating notch 24 therefor will conduce to a high degree of stability of the legs and sturdiness of the supported structure.

The arrangement described fully obviates any need for the usual corner braces and the like, 50 and enables the corner assembly to be completed by utilizing in a small, light weight unit, no more than a single holding element such as the hanger bolt, in each corner region, and utilizing a pair or more of the bolts HB in each 55 corner of a larger or heavier article such as a table of some weight or size.

Although the invention has been described by 60 particularized reference to the parts and arrangement of a currently preferred embodiment, the detail of description should be understood solely in an illustrative rather than in any limiting sense, numerous variants being possible within the intended scope of the claims hereunto appended.

65 I claim as my invention:

1. In a table, a leg and apron assembly including in combination with the table top, a substantially rectangular arrangement of aprons edge-wise attached beneath the table top and some- 70 what inwardly of the margins thereof, certain of said aprons being extended endwise exteriorly beyond the enclosure formed by the aprons, one of the aprons in each corner region thereof being recessed to provide a pair of V-shaped notches 75 on opposite sides of the apron and apertured

horizontally between said notches to receive one or more hanger bolts, a leg having one of its edge portions conforming to and snugly wedged into one of the paired notches in a manner to position the leg angularly with respect to the apron, one or more hanger bolts extending through the apertured portion of the notched apron between the notches, thence substantially horizontally into an upper portion of the adjacent leg, a nut in the other notch of the pair, for engaging each hanger bolt, the cornering region of the aprons being formed to provide a tongue and slot connection, and the adjacent apron extension being formed with an oblique face adapted to abut and position a side face portion of the upper end of the adjacent leg, and a holding element extending through the leg substantially along the axis of the adjacent apron extension.

2. In an article of furniture having a flat supporting top and legs therebelow, a substantially rectangular arrangement of aprons edgewise attached beneath the supporting top and somewhat inwardly of the margins thereof, certain of said aprons being extended endwise exteriorly beyond the enclosure formed by the aprons, one of the aprons in each corner region thereof being recessed to provide a V-shaped notch on one side of the apron, the last said notched apron being formed to provide an oblique seat opposite and parallel to one face of the V-shaped notch, said notched apron being apertured horizontally between said seat and said opposite and parallel

notch face to receive one or more bolts, a leg having one of its edge portions conforming to and snugly wedged into the V-shaped notch in a manner to position the leg angularly with respect to the apron, one or more bolts extending through the apertured portion of the notched apron between the oblique seat and said parallel notch face, thence substantially horizontally into an upper portion of the adjacent leg, a nut positioning on said oblique seat for engagement with each bolt, the cornering region of the aprons being securely attached together, and the adjacent apron extension being formed with an oblique face adapted to abut and position a side face portion of the upper end of the adjacent leg, and a holding element extending through the leg substantially along the axis of the adjacent apron extension.
